CLAIM

The ornamental design for an electrode track section, substantially, as shown and described.

DESCRIPTION

FIG. 1 is a top perspective view of an electrode track section showing our new design;

FIG. 2 is a bottom perspective view thereof;

FIG. 3 is a cross-sectional view thereof at the location indicated in FIG. 1;

FIG. 4 is a cross-sectional view thereof at the location indicated in FIG. 1;

FIG. 5 is a top view thereof;

FIG. 6 is bottom view thereof;

FIG. 7 is a front view thereof;

FIG. 8 is a rear view thereof;

FIG. 9 is another top perspective view thereof, showing portions of an attached electronic module such as a track light fixture as environmental structure; and,

FIG. 10 is a bottom perspective view of FIG. 9.

The dot-dash lines in the figures immediately adjacent to the shaded regions define boundaries of the claimed design. The other broken lines showing environmental structure in the figures are for illustrative purposes only and forms no part of the claimed design. The shade lines in the figures show contour and not surface ornamentation.

1 Claim, 3 Drawing Sheets
